UNITED STATES PATENT OFFICE.

HENRY M. LANE, OF DETROIT, MICHIGAN.

CONVEYING MECHANISM.

1,274,900.

Specification of Letters Patent. Patented Aug. 6, 1918.

Application filed April 29, 1918. Serial No. 231,377.

To all whom it may concern:

Be it known that I, HENRY M. LANE, a citizen of the United States, residing at Detroit, in the county of Wayne and State of Michigan, have invented certain new and useful Improvements in Conveying Mechanism, of which the following is a specification.

This invention relates to conveying mechanism; and it comprises a conveying system for foundries and the like wherein elevated trolley carriages and traveling cranes are employed, the system consisting of an overhead track on which trolleys are run, the overhead track being provided with switches at certain intervals, in combination with traveling cranes running on suitable tracks and generally at an angle to the trolley tracks, and provided with girders or transfer bridges, the crane girders or transfer bridges being adapted to form tracks for said trolley to permit the trolley to be run on and off the cranes, said girders being arranged at an angle to the direction of travel of the cranes and adapted to form a continuation of the switch tracks; all as more fully hereinafter set forth and as claimed.

In a foundry layout the building is generally divided into a number of separate spaces which are termed bays. An overhead trolley track is arranged usually at one side running the entire length of the building, and it is connected to a similar track which runs to the cupola or furnace. Traveling cranes running on tracks at substantially right angles to the main trolley tracks are provided for each bay, and said cranes are generally provided with a girder or transfer bridge, arranged in the same plane as the main tracks, thereby permitting the trolley to move from the main tracks on the crane, and be conveyed by the crane to a molder's flask or flasks located in the bay.

At the present time, foundries are provided with traveling cranes arranged in the bays, one crane being provided for each bay. The transfer bridges of the cranes are arranged at right angles to the direction of travel of the cranes and are adapted to form the main trolley track when all of the cranes are alined. The difficulty in the use of a system of this character is that when one of the cranes is moved down the bay, the track is broken. Under such circumstances, if a molder in a bay toward the end of the build-

ing wishes to get supplies, and one of the cranes nearer to the furnace has been moved down the bay, he must wait until this crane is brought back into position to complete the track before he can move his ladle to the furnace.

When a main trolley track is provided, the transfer bridges or girders have also been arranged at right angles to the wheels of the crane, and parallel to the main trolley tracks. A construction of this character necessitates the use of very complicated switching mechanism, turn tables and the like and presents serious difficulties. The cost of installing and operating complicated switching mechanism for each bay of a large foundry is very great and the delay occasioned in conveying the molten metal to the flasks is a serious consideration. In addition it is somewhat difficult to handle the trolleys carrying the molten metal and there is a great possibility of accidents in transferring the trolley to the crane.

In the present invention I have devised a very simple method of transferring the trolley from the trolley tracks to the transfer bridge or girder of the crane. The transfer bridge is arranged at an acute angle to the trolley tracks and substantially in alinement with the switch rail of the trolley tracks when the switch is in open position. This permits the trolley to be transferred from the tracks to the crane by the simple expedient of an ordinary switch, the trolley being run on to the switch track, and from the switch track passing on to the transfer bridge which is arranged in alinement with the switch track.

In the present invention I employ an overhead trolley track which is shown of the monorail type and provide a plurality of switches of ordinary construction, the switches being spaced along the track so as to provide a switch for each bay, and a traveling crane arranged in each of the bays and running on tracks, the crane being provided with a pair of wheels on each side, the front wheel on one side being in alinement with the rear wheel on the other side and connected by a squaring shaft, and the crane being further provided with a transfer bridge or girder arranged in the same plane as the switch tracks and being arranged at an angle to the squaring shaft, the transfer bridge being adapted to form a

continuation of the switch track when the switch is open and the crane is properly positioned with respect thereto.

In the accompanying drawings I have shown several advantageous embodiments of the invention. In this showing

Figure 1 is a diagrammatic plan view showing a foundry layout in accordance with this invention;

10 Fig. 2 is a vertical sectional view taken on the line 2—2 of Fig. 1;

Fig. 3 is a detailed plan view showing one of the cranes in alignment with a switch track, and showing a trolley on the transfer bridge of the crane;

15 Fig. 4 is a side elevation of the construction shown in Fig. 3;

Fig. 5 is a diagrammatic plan view of a foundry layout showing the main trolley track provided with a return track, and showing bays arranged on each side of the main track and

20 Fig. 6 is a plan view of the crane showing the squaring shaft provided with a universal joint.

Referring to Fig. 1 of the drawings, the foundry A is divided into a number of bays or "floors" 1 and a main trolley track 2 is arranged at one side of the building. A 25 loop 3 in the trolley track passes the furnaces 4. Branch track 5 may be employed for conveying sand molds, equipment, etc., into the foundry. The branch track is connected to the loop by a switch 6. At the other end of the building the main track may be continued outside of the building to permit the trolleys to be used for conveying flasks, etc., into the building (not shown). The main track is provided with a 30 plurality of switches 7, one switch being provided for each of the bays except the end one. The main track terminates at the end of the next to last bay, as at 8. Switches 9 and 10 connect the main track to the loop. 35 The transfer bridges of the crane are indicated in dotted lines in Fig. 1 as at 11 and, as shown, are adapted to form a continuation of the switch tracks when arranged in proper position. Connecting tracks 12 are 40 arranged between the end of the switch and the end of the transfer bridge. The last bay is provided with the ordinary type of crane in which the transfer bridge is arranged parallel to the main tracks, and 45 when the crane is run to the extreme end of the bay it forms a continuation of the main tracks as indicated in dotted lines at 13.

In Fig. 2 of the drawings, the main track, a switch rail and a transfer bridge are shown 50 and designated by the same reference numerals as in Fig. 1. In this view is shown a supporting girder 14 upon the top of which is arranged a track 15 for the crane. The girders 14 are a part of the main frame 55 work of the building and are supported by

vertical posts 16. Girders 17 are arranged at right angles to the girders 14 and connected to them by suitable means at 18.

In Figs. 3 and 4 of the drawings, the construction of the crane and the switching mechanism are shown in greater detail. The crane is best provided with four wheels which travel on tracks 15 and, as shown, the front wheel 19 on one side of the crane is in transverse alignment with the rear wheel 20 75 on the opposite side of the crane and is connected thereto by squaring shaft 21. The transfer bridge 22 is carried by the depending supports 23 and is arranged at an angle to the squaring shaft. Any type of mechanism may be employed for operating the switches. In the drawing I have illustrated a switching mechanism of an ordinary type. In this construction the switching mechanism is supported by girder 24 80 and carries a pulley or wheel 25. A chain 26 passes over the pulley, and is provided with depending handles (not shown) the handles extending down a suitable distance within reach of the person operating the 85 switch. Connecting rod 27 is connected to the pulley and is also connected to switch block 28. This block is arranged on the end of the switch. Switch block 28 carries rollers 29 which travel on girder 24. When the pulley is revolved the crank moves the switch block thereby throwing the switch rail into position. The switch block is provided with extensions, not shown, which abut against the open end of the track and 90 prevent the trolleys from running into an open switch. In Figs. 3 and 4 I have shown a trolley 30 on the transfer bridge. The trolley best comprises a substantially U-shaped frame 31 carrying rollers 32. The 95 rollers are adapted to run on the lower flange of the trolley tracks and transfer bridges, which, as shown, are best made of I-beams. The trolley frame is provided with a hook or eye 33 to which is secured 100 the rod 34 which carries the ladle or pot of molten metal or other material.

In the construction shown in Fig. 5 of the drawings I have shown the main trolley system provided with a return track. The 115 main track 35 is similar to the track shown in Fig. 1 and is provided with switches 36 for each of the bays. Connecting tracks 37 are provided near each switch. The return track 38 is provided with switches 39 at 120 suitable intervals connecting it to the main track. In this instance I have shown the tracks arranged in the center of the building with bays 40 arranged on one side of the track and bays 41 on the opposite side. As 125 shown there are two main tracks 35 and 35' which may be operated with a single return track. The main track 35' is provided with switch 36' and connecting tracks 37'. It is connected to the return track by switches 130

39'. The loop 42 is provided at one end with a switch 43 connecting it to either the return track 38 or to a section of track 44. This section is connected to the main track 5 by one of the switches 36. At the other end, the loop is provided with switch 45 connecting it to the opposite section of the return track or to the main tracks 35 and 35'.

In Fig. 6 of the drawings, I have shown 10 a crane in which the wheels 19 and 20 are not in alinement, and in which the squaring shaft is provided with a universal joint 46. It is advantageous to connect one wheel on one side of the crane with a wheel on the 15 other side of the crane by a shaft so that the wheels will run at the same speed and therefore eliminate the possibility of the crane jumping the track. However, it is not absolutely necessary to have wheels 19 and 20 in alinement, as they can be connected by a universal joint as shown in Fig. 6.

The method of employing this system in the form shown in Figs. 1 to 4 of the drawings is as follows:—

25 When a molder in one of the bays 1 wishes to obtain molten metal from the furnace the crane, carrying the bucket or other receptacle for the metal is moved over track 15 to the end of the bay and the transfer bridge 30 22 is alined with the connecting rail 12 and the switch 3, the switch being arranged in open position as shown in Fig. 1. The trolley is run over the connecting rail on to the switch, and from there it passes on to the 35 main rail 2. The trolley is propelled along the main rail by the workman, any suitable means being employed for this purpose. Any open switches are closed by hand the trolley being moved toward the loop 3. 40 When switch 9 or 10, as the case may be, is reached, the switch is thrown into position to connect it to the loop and the trolley is run into the loop. The ladle is then filled with molten metal and run over the other 45 switch (9 or 10) back on to the main tracks. The trolley is then moved over the main tracks in the opposite direction until the switch leading to the bay in which the metal is to be used is reached. The trolley is run 50 past the bay and the switch is opened and the trolley backed on to the switch from whence it passes on to the connecting rail 12. The crane is arranged with the transfer bridge 22 in alinement with the connecting 55 track and the trolley passes from the connecting track to the transfer bridge. The crane is then moved along tracks 15 to the flask.

When the present system is employed in 60 a foundry of relatively large size it is advantageous to provide a return track as shown in Fig. 5. In the foundry layout shown in Fig. 1 of the drawings it is only possible for trolleys to be traveling in one direction at a time and if one trolley is mov-

ing from the loop to a flask, a second trolley which is ready to be moved in the opposite direction has to wait until the track is clear. As a matter of fact, in a small foundry this condition arises so seldom that it is negligible and it is better to employ the single track system at an initial saving in the cost of installation. In a foundry of greater capacity, however, delays of this sort are more frequent and it is advantageous to 70 install the return track system at a greater initial cost in order to avoid such delays.

In the construction shown in Fig. 5 of the drawings the trolleys travel from the bays 40 and 41 to the loop 42 over return 80 track 38 and return to the bays over main tracks 35 and 35'. When a trolley is to be carried from one of the bays 40, shown to the left of loop 42, the trolley passes on to main track 35 over switch 36 in a manner 85 similar to that employed in the form shown in Fig. 1. The trolley then passes over switch 39 on to the return track 38 and from there it passes over switch 43 to the loop 42. When the receptacle has been filled with 90 molten metal, switch 45 is arranged to connect loop 42 with the main track 35 and the trolley is passed on to the main track 35 to the right of the loop. From there it travels in a reverse direction over main track 35 95 to the switch 36 connecting the main track with the crane in the desired bay. A trolley in one of the bays 40 to the right of the loop is run on to the main track 35 in the same manner as just described, thence over 100 switch 39 to return track 38. Switch 45 is arranged to connect return track 38 with loop 42, and the trolley is run on to the loop. After it has received the molten metal it is run over switch 43 on to the short section 105 of track 44 and the switch 36 is thrown to its extreme position connecting track 44 with the main track. The trolley passes along the main track, over switch 36, over the connecting track 37 to the transfer 110 bridge 22.

When the trolley is in one of the bays 41 it is run on to the main track 35', over switch 39' on to return track 38, whence it passes to the loop in the manner just described. 115 From the loop the trolley may be backed out over switch 45 on to main track 35' whence it is returned to bay 41, or, if another trolley has come into the loop and the track is not clear thereby preventing it from backing; it may pass from the loop over switch 43 and run along main track 35 to one of the switches 39. From the switch 39 it may pass on to return track 38, thence over switch 39' to main track 35'.

In the specification I have described my invention in connection with foundries, and employed as means for conveying molten metal from the furnaces to the flasks. However, I do not wish to limit myself to this 120

particular utilization of the invention, since the system may be employed in connection with any type of plant in which a trolley runs from one point in the plant to another, 5 by means of an overhead trolley system, and a traveling crane. The above description of the invention is meant to be illustrative rather than restrictive.

What I claim is:—

- 10 1. An overhead trolley system, in combination, a main track, a traveling crane arranged to travel at an angle to the main track, a transfer bridge carried by the crane, and switches for the main tracks, the transfer bridge being arranged at an angle to the crane and in alinement with one of said switches when the switch is in open position.
- 15 2. The combination with an overhead trolley system provided with a switch track, of a traveling crane, having a transfer bridge arranged at an acute angle to the crane, the transfer bridge being arranged to aline with the switch track when in open position and to form a continuation of the switch track.
- 20 3. A traveling crane having forward and rear wheels, the forward wheel on one side of the crane being substantially in alinement with the rear wheel on the opposite side of the crane, a squaring shaft connect-

ing said alined wheels, and a transfer bridge 30 carried by said crane at an angle to said squaring shaft.

4. In a foundry layout having a plurality of bays, the combination of a main track provided with switches for each of said bays, a traveling crane in each bay, and a transfer bridge carried by each of said cranes, said transfer bridge being arranged at an angle to form a continuation of said switch track when the switch is in open position. 40

5. In a foundry layout having a plurality of bays, the combination of a main track provided with switches for each of said bays, a traveling crane in each bay, a transfer bridge 45 carried by each of said cranes, said transfer bridge being arranged at an angle to form a continuation of said switch track when the switch is in open position and a connecting track between the transfer bridge and switch 50 track.

6. A traveling crane provided with wheels, a transfer bridge, the transfer bridge being arranged at an acute angle to the axes of the wheels. 55

In testimony whereof, I affix my signature hereto.

HENRY M. LANE.
